UNITED STATES PATENT OFFICE.

JAMES C. COOPER, OF BALTIMORE, MARYLAND, ASSIGNOR OF ONE
FOURTH TO JOHN G. LANG, OF BALTIMORE CITY, MARYLAND.

BROOM-PROTECTOR.

No. 839,057.

Specification of Letters Patent.

Patented Dec. 18, 1906.

Application filed July 11, 1906. Serial No. 325,586.

To all whom it may concern:

Be it known that I, JAMES C. COOPER, a citizen of the United States, residing at Baltimore city, State of Maryland, have invented certain new and useful Improvements in Broom-Protectors, of which the following is a specification.

My invention relates to an improvement in a device for the protection of brooms; and the object of the same is to decrease the liability of the broom from spreading when used in sweeping rough surfaces, thereby rendering the broom stiff, so that the straw is not likely to become broken, as would ordinarily be the result when being used in the sweeping of rough surfaces; and the device is particularly adapted to a broom when used to clean narrow crevices, such as railway crossings and switches. It is also applicable for use on brooms for household purposes, as well as on brooms for all other purposes where brooms of this particular character are used.

With the foregoing object in view my invention consists in certain novel features of construction and combination of parts, which will be hereinafter described, and pointed out in the claim.

In the accompanying drawings, Figure 1 is a perspective view of my invention. Fig. 2 is a view showing the device secured on a broom, and Fig. 3 is a view of a thumb-screw used for the purpose of securing adjustment of the device on the broom.

A represents two vertical parallel metal rods, and 1 a circular band formed at the top part thereof. These rods and the band can be stamped out of a single piece of sheet metal, as shown in the drawings, or can be made separately and secured together by any suitable means as may be desired or found the most advantageous in the manufacture thereof. These rods are made from sheet metal of a suitable thickness to afford stiffness and strength.

2 is a metal band corrugated at 3 3 and secured to the rods A by means of the rivets 4 4.

A hole is drilled and threaded (not shown) in the circular band 1, into which is fitted the threaded thumb-screw 5, while 6 is a trian-

gular opening cut in the rod A for the purpose of securing the broom on a nail or other suitable object when not in use.

B represents the handle of a broom, and C 55 the straw body portion.

The device is operative as follows: It is first slipped over the handle B with the circular band 1 around the handle, as shown in Fig. 2, and is forced over the body portion C 60 until the band 2 is of sufficient distance from the sweeping edge of the body C, according to the stiffness desired to be had of the body part C for the required purpose of use. It is then secured in this adjustment by screwing 65 the thumb-screw 5 against the handle and is then ready for use. The corrugations 3 3 of the band 2 perform the function of holding the straws of the body portion C in their distributed position and prevent them sliding 70 to one end when using the broom edgewise.

From the foregoing it will be seen that a simple and effective device is provided whereby a broom is held in its original shape and the spreading and breaking of the straw 75 material of which it is composed is to a great extent thereby lessened and the life of the broom prolonged.

Slight changes might be resorted to in the form and arrangement of the several parts 80 described without departing from the spirit and scope of my invention, and hence I do not desire to limit myself to the exact construction as herein set forth; but,

Having described my invention, what I 85 claim as new, and desire to secure by Letters Patent, is—

A broom-protector substantially as herein-before described, comprising two vertical parallel metal rods, a circular band formed 90 on the top part thereof, a thumb-screw in the band, and an oblong corrugated band secured on the lower ends of said rods, a triangular opening being provided in the lower end portion of one of the rods for the purpose as 95 herein set forth.

In testimony whereof I affix my signature in presence of two witnesses.

JAMES C. COOPER.
